HAIR CURL HOLDER PIN

Alma Wittman, Petersburg, Mich.

Application May 18, 1946, Serial No. 670,662

1 Claim. (Cl. 132—46)

2

My invention relates to a toilet article for dressing the hair and provides a hair curl holder pin for positioning the hair in ringlet form. Particularly, the invention relates to a curl holder pin which may be used advantageously to grip various sized ringlets of hair. Further the invention relates to a curl holder pin which the user may apply to its curl holding position with but one hand, freeing the other hand for manipulation of the hair.

The invention has for an object to provide an efficient curl holding device so completely encompassing the curl ringlet and retaining the same in position as to eliminate the need for the number of pins normally used in setting the hair. It has been observed that in order to prevent a hair ringlet from slipping out of its curled position, two or three hairpins of the well known construction must be carefully inserted into each curl.

My predecessors in this art of providing a single curl holder pin utilize an article having a plurality of arms which radiate from a common center, each of which is provided with end hooks purposed to engage the curl peripheral portions only. Devices of this character have limited adaptability in that the length of the arms positively determines the size of the ringlet that may be held. Thus, in order to cope with ringlets of various sizes a kit of various sized pins is required. These prior art devices are further of limited efficiency because they engage only one face of the curl, except that the hooked ends may slightly overlap the otherwise free other face. My invention is a considerable improvement over such prior art devices in that it is capable of holding curl ringlets of a great variety of sizes and has provision for clasping both faces of the curl ringlet.

My invention, therefore, has for a particular object to provide a hair curl holder pin formed of wire and bent to have a substantially diamond shaped web portion positioned by and with respect to the hair engaging legs and other parts of the pin so that the hair curl may be located between the legs and the web and so that the web extends substantially across the whole face of the ringlet to press the ringlet between the web and legs. Consequently only a single hair curl holder pin of the character proposed by my invention is required to position each ringlet. The advantages of time and savings to the user gained thereby will be readily apparent.

A further particular object of my invention is to provide a hair curl holder pin which prevents

the dislodgment of a positioned ringlet from its desired arrangement. Prior art structures provide hinged clamping bars to position the curl. However, these devices are time consuming, inconvenient and awkward to operate, thus causing the disarrangement of positioned adjacent ringlets in placing the pin to grip a curl. The embodiment in my device of a crenated leg section located in clamping registration with the web, 5 serves to grip the entire ringlet firmly in its desired location without dislodgment of neighboring ringlets, as each curl is positioned.

My invention has for a further particular object to provide a hair curl holder pin that can 15 be used advantageously in connection with any size ringlet usually employed in setting the hair. The contouring of the web provides for the firm retention of a relatively small or large curl.

The invention consists in other features and 20 advantages which will appear from the following description and upon examination of the drawings. Structures containing the invention may partake of different forms and still embody the invention. To illustrate a practical application of 25 the invention, I have selected a hair curl holder pin as an example of the various structures and details thereof that contain the invention and shall describe the selected structure hereinafter, it being understood that variations may be made 30 without departing from the spirit of the invention. The particular structure selected is shown in the accompanying drawing and described hereinafter.

Fig. I of the drawings illustrates a plan view 35 of the hair curl holder pin embodying the features of my invention. Fig. II is a side elevational view of the hair curl holder pin. Fig. III illustrates somewhat diagrammatically the operation and final position of the curl holder pin 40 relative to a ringlet of hair.

The particular embodiment of the curl holder pin shown in the accompanying drawing is preferably formed of a single strand of resilient wire, bent to have leg members 1 and 2 with splayed 45 end portions 3 and 4 integral therewith. Preferably the leg members each have crenated sections 7 and 8 intermediate their ends which provide means for gripping the ringlet more firmly and preventing dislodgment of the ringlet, as will appear more clearly hereinafter. The ends of the legs 1 and 2 opposite to the splayed portions 3 and 4 are brought into engagement with one another and twisted to form a depending shank 9. The shank 9 extends between and in substantially 55 parallel and equally spaced relation to the legs

and is bent slightly outwardly from the plane common to the legs to provide space between the shank and legs.

Extending from the shank 9 is a loop of wire bent to form a substantially diamond shaped web 12 having U-shaped points 13, 14 and 15 and connecting stretchers 17, 18, 19 and 20. The stretchers 17 and 18 extend from shank 9 and are curvedly bent toward the plane of the legs to locate the points 13 and 14 in near registration with the plane of the legs 1 and 2 as shown in Fig. II of the drawings. Stretcher 19 joints the points 14 and 15 and stretcher 20 the points 13 and 15. The portions 19 and 20 are bent from the plane of the legs to locate the point 15 in spaced relation to the plane of the legs and define a wedge shaped space in which the hair curl may be easily directed.

Preferably, the angle at which stretchers 19 and 20 extend to the legs 1 and 2 is of the magnitude of 5°, as shown in Fig. II of the drawings. It has been found that a point with an angle of less than 5° will not as readily slide over the face of the ringlet and tends to entangle the coiled hair, while an angle of more than 5° permits slippage of the coiled hair and will not grip the ringlet securely, especially when the hair is arranged in small coils.

In affixing the hair curl holder pin to a ringlet to be positioned, the hair is coiled into a ringlet 22 substantially as shown in Fig. III. The end portions 3 and 4 of the leg members 1 and 2 are then slipped under the ringlet 22, and member 12, guided by the point 15 and stretchers 19 and 20, is yieldingly displaced by the body of the ringlet 22, relative to the legs 1 and 2 to engage resiliently the face of the ringlet 22, as illustrated in Fig. III of the drawings. The crenated sections 7 and 8 bite into the under face of the curl and hold the ringlet 22 despite the tendency of the displaced web member 12, relative to the legs, to squeeze the ringlet from between it and the legs.

A ringlet of the relative size of the ringlet 22 or a ringlet of a diameter approximately that of the distance between the points 13 and 14 may be held with equal facility. The clincher relation of the points 13 and 14 to the crenated sections 7 and 8 of the legs assures a resilient but firm grippage of the coiled hair at many spaced points relative to the neutral axis of the web member 12 and the center of the coil of hair. While I have illustrated and described the best form of my invention now known to me, as required by the

statutes, those skilled in the art will readily understand that changes may be made in the disclosed construction without departing from the spirit of my invention as set forth in the appended claim.

5 I claim:

In a hair curl holder pin comprising a single strand of resilient wire having two opposite end lineal portions extending substantially in spaced parallel relation and a pair of intermediate lineal portions immediately adjoining each of said end portions extending in helical continuity and close wrapped relation to each other and conjointly extending in spaced parallelism with and between said end lineal portions through a plane parallel to the plane of extension of said end lineal portions, characterized by the provision of a central lineal portion whose opposite ends immediately adjoin said pair of intermediate lineal portions and which extends therebetween in loop continuity of the form substantially like that of a trapezium with three U-shaped vertices, said closely wrapped intermediate lineal portions adapted for supporting the trapezium looped central lineal portion spaced from opposite ends of said parallel end portions to locate one of said U-shaped vertices at a point on a plane extending parallel to and spaced from said plane of extension of said end lineal portions and equi-distant from and between said end lineal portions and each of the other two of said U-shaped vertices at a point on said plane of extension of said end lineal portions exterior to the space between said end lineal portions and spaced from each of said end lineal portions, said intermediate and central lineal portions providing means adapted to span one side of a hair curl, spiderwise, and clamp the hair curl against the end lineal portions, the hair of perimetrical coils of the curl being crimped and locked between each of said last named U-shaped vertices and one of said end lineal portions.

ALMA WITTMAN.
